UNITED STATES PATENT OFFICE.

HENRY E. DREVES, OF CLEVELAND, OHIO, ASSIGNOR TO THE H. N. WHITE COMPANY, OF CLEVELAND, OHIO, A CORPORATION OF OHIO.

SAXOPHONE AND OTHER REED INSTRUMENTS.

Application filed June 30, 1923. Serial No. 648,715.

To all whom it may concern:

Be it known that I, HENRY E. DREVES, a citizen of the United States, residing at Cleveland, in the county of Cuyahoga and 5 State of Ohio, have invented certain new and useful Improvements in Saxophones and Other Reed Instruments, of which the following is a specification.

The present invention relates to an improvement in musical instruments and more particularly saxophones and reed instruments and the general object of the invention is to provide such instruments with an octave hole or socket which 15 will in use facilitate a rapid change from one register to another, make the octave tones clearer in quality, prevent striking of air against the closure pad for the opening in a way to avoid buzzing, hissing or other objectionable effects when the 20 pad is raised, and assure a quick effective and unobstructed opening.

In the drawing accompanying this application, Fig. 1 is a side view of a saxophone on a reduced scale, showing in full lines the mouth pipe in which one of my improved octave sockets is located, the main body of the instrument being shown in dotted lines. Fig. 2 is an enlarged side view 25 of the mouth-pipe with the socket member and pad in section. Fig. 3 is a cross section considerably enlarged, on lines 3—3 of Fig. 2. Fig. 4 is an enlarged top view of the socket member itself.

In a saxophone the octave holes or sockets are used to produce tones one octave above those of the lower register extending the compass of the instrument one full octave above the actual pitch by length of pipe. 35 The sounding of these upper tones is done by operating octave keys to open holes, that in effect cut the effective pitch length of the pipe in half, thus doubling the number of sound vibrations per second. To "cut" the effective pitch length of any pipe without impairing tone quality, an opening of very small size must be made at approximately the middle point of the pitch length. This opening gives a vent at a point in the sound 45 wave formation called the node, thus splitting the sound wave and causing it to form in one half its previous length and raising the pitch one octave.

The opening of this vent must be as un- 50 obstructed as possible when in use in order

to facilitate the rapid change from one register to another. Heretofore this vent or octave hole has been drilled on a straight line axially through the octave socket member. When the pad is lifted it does not 60 provide a quick effective means of "venting" this point. A buzzing noise due to the release of the alternating pressures at the nodal point and the air striking the pad 65 characterizes the opening of this hole and is most noticeable in D, G and A in a saxophone. In brief, this "sluggishness" of action and buzzing does not permit rapid execution of octave "jumps", clearness of tone etc., as the notes in the upper register 70 do not respond immediately to the opening of an axially drilled socket.

To avoid the "buzzing" or striking of air against the pad and to make the octave tones clearer in quality, and to provide a quick, 75 sure, effective and unobstructed opening, I drill a hole 2 in a socket member 3 on a slant with respect to the motion of the pad 4. As a result, the pad upon raising vertically does not obstruct the opening of the 80 hole and provides an unobstructed vent at the desired point. This eliminates all hissing, buzzing or other disagreeable features attached to the old type of socket.

Socket member —3— comprises a semi-spherical head 6 having a reduced stem 7 at its bottom which is adapted to extend through the pipe or tubular mouth-piece 5 and to be secured thereto in any suitable mechanical way. The soft sealing pad 4 85 at the end of the pivoted key —8— is concaved to fit the round head when seated snugly thereon and it covers the round outlet end of opening —2—, which outlet it should be noted is situated at one side of 90 the axial center of the round head relatively near the rounded bottom edge 9 of the pad, see Fig. 3. This offset relation of the outlet in respect to the center of the cavity in the pad is obtained by drilling a 100 straight hole through the head and stem at an inclination to the vertical axis of member —3—, and the bottom or inner entrance to the bore or hole is also offset in respect to the axis of the member and it may intersect the bottom corner of the stem in a plane substantially flush with the curved inner surface of the tube or pipe to obtain the best results. Member 3 is also preferably affixed to the tube or pipe with the inclined 105 110

bore 2 extending tangentially to the circular wall of the tube or mouth piece of the instrument as shown in Fig. 3.

As shown member 3 is applied to the mouth-pipe, but it may be applied to other parts of a wind instrument. In a saxophone, two such socket members are generally used, one on the mouth-pipe, and one on the upper end of the body.

10 What I claim, is:

1. A wind instrument having a padded key and a rounded valve seat having a vent opening offset in respect to the center and edge of both the seat and the pad of the key.

15 2. A wind instrument having a padded key and a socket member provided with an inclined vent opening offset in respect to the center of said pad.

3. A wind instrument having a key provided with a concaved pad, and a rounded seat for said pad having an opening at one side of the axis of said seat and pad.

20 4. A wind instrument having a key provided with a concaved pad, and a semi-spherical seat for said pad having an inclined opening therein terminating at one side of the center of said pad.

5. In a saxophone or other reed instrument, an octave valve member having an axially inclined opening, and a movable pad 30 adapted to seat the edge portion thereof over the outlet end of said opening.

6. In a saxophone or other reed instrument, a pivoted key having a concaved pad, and a rounded seat for said pad having a 35 vent opening at one side of the center of both said pad and seat.

7. In a saxophone or other reed instrument, a mouth pipe having a rounded protuberance with a slanting vent opening 40 therein, and a pivoted key having a soft concaved pad adapted to seat axially opposite said protuberance with the mouth of said opening near the edge of the pad.

8. In a saxophone or other reed instrument, an octave valve member comprising a semi-spherical head and a reduced stem, said stem and head having an opening extending therethrough at an inclination to the axis thereof. 45

In testimony whereof I affix my signature hereto.

HENRY E. DREVES.
